UNITED STATES PATENT OFFICE.

HENRY W. NELSON, OF NEW YORK, N. Y.

CONCRETE-MIXER.

1,235,589.

Specification of Letters Patent. Patented Aug. 7, 1917.

Application filed February 15, 1912, Serial No. 677,765. Renewed May 8, 1917. Serial No. 167,369.

To all whom it may concern:

Be it known that I, HENRY W. NELSON, a citizen of the United States of America, and a resident of the borough of Manhattan, 5 city, county, and State of New York, have invented a new and useful Improvement in Concrete-Mixers, of which the following is a specification.

My invention relates to concrete mixers 10 and has as its object a means of the character set forth which is simple in construction, easy of operation and of a higher efficiency than those heretofore used. One of the essential features of my invention comprises 15 a plurality of hopper shaped compartments, substantially oppositely arranged in pairs, with means for discharging the mix from either one of the hopper shaped compartments of one pair into the other of the same 20 pair, in combination with means for charging and emptying said compartments.

In the following I have described, in connection with the accompanying drawings, one embodiment of my invention, the features thereof being more particularly pointed 25 out hereinafter in the claims.

In the drawings Figure 1 is an end view 30 of a structure illustrating my invention, partly in section and partly broken away. Fig. 2 is a top plan view, parts being broken away.

Similar numerals of reference indicate similar parts throughout the several views.

In the drawings 1, 2, 3 and 4 indicate a 35 plurality of hopper shaped compartments, here shown as four in number, oppositely arranged in pairs, compartment 3 being opposite compartment 1 and compartment 4 being opposite compartment 2. Each of said 40 compartments is preferably substantially funnel shaped, inclining inwardly from top to bottom, the top periphery being preferably slightly elliptical with the shorter diameter transversely of the apparatus. The 45 compartments may be made of any suitable material, such as sheet iron or steel. The walls of the contiguous compartments are shown as bolted together at the tangential line by bolts 5. There is an opening 6 in the 50 bottom of each compartment so arranged that compartment 1 can discharge into compartment 3, and vice versa, through their respective openings, and compartment 2 can discharge into compartment 4, and vice 55 versa, through their respective openings.

8, 8 and 9, 9 indicate downwardly or outwardly turned flaps at the ends of the compartments and secured thereto by plates 7. The flaps overlap the flaps of the adjacent compartment, as shown in Fig. 1, in such 60 manner as to restrict the open space at the meeting point of the respective compartments and to form a guide-way for the mix from one compartment to the oppositely disposed one. A space 10 may be left to form 65 a sight hole for observation purposes. The corners of the flaps may be strengthened with suitable angle irons (not shown) if desired.

The compartments are closed at the top 70 by cylinder casing or wall 11 passing completely around the periphery of the apparatus, the upper edges of the walls of the compartments being provided with flanges 12 adapted to be secured to the casing 11, by 75 rivets or other suitable means. A door 13 is provided in the casing 11 for each compartment, each door being hinged to the casing at 14 and secured at its other side by a suitable bolt 15. 16, 16 are toothed racks secured to 80 the outer periphery of casing 11 and adapted to engage driving gears 17, 17, on shaft 18 driven by any suitable power. Shaft 18 also carries idler wheels 19, 19 adapted, in connection with similar idlers 20, 20 on 85 shaft 21 on the other side of the apparatus, to support the apparatus and to take the weight off of the driving gears. Casing 11 is provided with suitable bands 22, 22, secured thereto, to serve as a trackway or bearing surface for the idlers. The several compartments are thus connected in circular series, with their discharge ends converging, and the mixer thus partakes of the nature of a rotatable drum. 95

The operation of the apparatus is as follows:

The apparatus being in the position shown in Fig. 1, for example, the door of compartment 1 is opened and a charge of cement, sand and gravel and water is introduced therein; the apparatus is then caused to rotate a quarter revolution in the direction of the arrow; the compartment 4 is then charged and the apparatus caused to 100 rotate a half revolution farther (a three quarter revolution in all), so that compartment 1 is above compartment 3 and discharges thereinto; the apparatus is then caused to rotate another quarter revolution 105 110

(a complete revolution in all), so that compartment 4 is above compartment 2 and discharges thereinto. The apparatus is then rotated until the mix has been discharged 5 from one compartment to the opposite one any desired number of times. I have found four discharges to give a good result. Starting with an empty apparatus this requires a rotation of two and a half times until the 10 first batch is discharged from the apparatus and the third batch is introduced into compartment 3. At two and three quarter revolutions, the second batch is discharged and the fourth batch is introduced into compartment 2. Thereafter two batches are 15 charged into the apparatus and two are discharged at the end of two complete revolutions each, so that I obtain one complete four time mix at an average of each revolution of the apparatus. The discharge takes place when the batch to be discharged is in position as in compartment 3, Fig. 1, when the lower wall of the compartment acts as a guide through the door 13 to the 20 place of discharge.

It is thus seen that I have provided a means for rapid and efficient mixing requiring but a minimum time of operation, the concrete mixers at present in use and 30 known to me discharging but one batch in from twelve to sixteen revolutions. I have also provided an apparatus subject to a minimum of wear and tear for any fixed amount of mixing, as well as operating under a low power cost of operation.

It is obvious that the details of construction may be varied, the number of compartments increased or diminished from those shown in the drawings and the shape of the 40 compartments changed without departing from the spirit of my invention and I do not restrict myself to the details as shown and described further than the scope of the appended claims demand.

45 What I claim and desire to secure by Letters Patent is:

1. In a concrete mixer, a series of pairs of hopper-shaped compartments closed at their larger ends save for inlet doors, the 50 smaller ends of each pair arranged in straight line opposition so as to discharge directly into one another as the mixer is turned over.

2. In a concrete mixer, a series of pairs of hopper-shaped compartments, means to close their larger ends, and doors in such closing means, and having the smaller ends of each pair arranged in line and close together so as to discharge from one to the 60 other as the mixer is turned over.

3. In a concrete mixer, a series of funnel-shaped compartments arranged in circular series, means to close their wider ends, and

means in said closed ends by which access is had into the compartments individually, 65 the apical ends of opposite compartments being arranged in line with one another so as to discharge from one into the other compartment as the mixer is turned over.

4. In a concrete mixer a rotatable drum 70 having therein a plurality of hopper shaped compartments substantially oppositely arranged with respect to each other and having discharge openings in communication with each other so as to permit the discharge from one of said compartments to the oppositely disposed one and vice versa and doors in the shell of said drum communicating with each of said compartments, said doors being so arranged with relation 75 to the walls of the respective compartments that the lower walls form a chute to the doors for the discharge from the apparatus.

5. In a concrete mixer a rotatable drum having therein a plurality of hopper shaped 80 compartments substantially oppositely arranged with respect to each other and having discharge openings in communication with each other so as to permit the discharge from one of said compartments to 85 the oppositely disposed one and vice versa, and means for guiding the discharge from one of said compartments to the oppositely disposed one.

6. In a concrete mixer a rotatable drum 90 having therein a plurality of hopper shaped compartments substantially oppositely arranged with respect to each other and having discharge openings in communication 95 with each other so as to permit the discharge from one of each of said compartments to the oppositely disposed one and vice versa and means adjacent the discharge end of said compartments for partially closing the space between said respective ends. 100

7. In a concrete mixer, a rotatable drum including a plurality of hopper-shaped compartments with converging discharge openings and a closed peripheral wall provided with a feed opening. 105

8. In a concrete mixer, a rotatable drum including a plurality of hopper-shaped compartments with converging discharge openings, means for guiding the discharging material from one compartment into the 110 discharging end of another, and a closed peripheral wall provided with a feed opening for each compartment.

In testimony whereof I have signed this specification in the presence of two sub- 115 scribing witnesses.

HENRY W. NELSON.
